US0D1056658S

(12) **United States Design Patent** (10) Patent No.: **US D1,056,658 S**
(45) Date of Patent: ** Jan. 7, 2025

(54) **DISMANTLING TOOL**

(71) Applicant: **Välinge Innovation AB**, Viken (SE)

(72) Inventor: **Karl Quist**, Höganäs (SE)

(73) Assignee: **VÄLINGE INNOVATION AB**, Viken (SE)

(**) Term: **15 Years**

(21) Appl. No.: **35/519,626**

(22) Filed: **Dec. 13, 2023**

(80) **Hague Agreement Data**

Int. Filing Date: **Dec. 13, 2023**

Int. Reg. No.: **DM/234136**

Int. Reg. Date: **Dec. 13, 2023**

Int. Reg. Pub. Date: **Jan. 5, 2024**

(30) **Foreign Application Priority Data**

Jun. 28, 2023 (EM) 015026374-0001

(51) LOC (15) Cl. **08-05**

(52) U.S. Cl.

USPC **D8/14; D8/89**

(58) **Field of Classification Search**

USPC D8/14, 21, 88, 89, 75, 81, 105
CPC B25C 11/00; B66F 15/00; E04D 15/00;
E04G 23/086
